UNITED STATES PATENT OFFICE.

ALFRED B. EVANS, OF PATERSON, NEW JERSEY.

DESIGN FOR A PITCHER OR SIMILAR ARTICLE.

SPECIFICATION forming part of Design No. 31,284, dated July 25, 1899.

Application filed July 1, 1899. Serial No. 722,607. Term of patent 3½ years.

To all whom it may concern:

Be it known that I, ALFRED B. EVANS, a citizen of the United States, residing at Paterson, in the county of Passaic and State of New Jersey, have invented and produced a new and original Design for Pitchers or Similar Articles of Manufacture, of which the following is a specification, reference being had to the accompanying drawings, forming part thereof.

The five portions hereinafter described together constitute my design for a pitcher or similar article of manufacture.

Figure 1 is a perspective view of a pitcher seen from one side, showing the portion of the design for the visible side of the bowl thereof, as well as the visible portion of the design for the handle and that for the rim and lip or spout. Fig. 2 is a perspective view of the front of the pitcher, showing the portion of the design on the front of the bowl thereof and the front view of the rim and lip or spout; and Fig. 3 is a perspective view of the pitcher from the reverse side, showing the portion of the design for the said reverse side of the bowl, as well as the visible portion of the design for the handle and that for the rim and lip or spout.

In each of the several views I have shown only the important and necessary portions of the design therein appearing. Thus in Figs. 1 and 3 I have omitted such portions of the design for the front of the bowl as would appear therein.

The five portions of the design are:

First. On the side of the bowl of the pitcher, as shown in Fig. 1, is a three-quarter view of the face of a man, with a small portion of the body above the shoulders, the face looking toward the right and wearing a mustache. The portion of the body is dressed in a standing shirt-collar and a suitable portion of a coat with turned-over collar, the coat fastened

at the throat and decorated on each side with a large button near the point of the collar there- 45 of. Around the upper half of the above is a rope tied in a loop at the top and which extends downward and ends in a turn at each end, and around the lower half of the face and shoulders, extending upward, is a spray 50 or branch of conventional laurel on each side, the ends thereof crossed below.

Second. On the reverse side of the bowl of the pitcher, as shown in Fig. 3, are enough of the important outlines to suggest a modern 55 war vessel floating or moving in water, with smoke flying from the stacks.

Third. On the front of the bowl of the pitcher, as shown in Fig. 2, are two conventional flags, consisting of dark and light colored stripes and a dark field showing five-pointed stars, the flags being mounted on poles or staffs, which are crossed, and being draped over the staffs, so that but little of either of them is visible, while placed above 65 the crossing-point of the staffs is a five-pointed star.

Fourth. The rim and lip or spout of the pitcher, as shown in the drawings, are suitably formed into a shape to suggest or represent the head, beak, and portions of the wings of an angry eagle, the beak being open to form the lip or spout and the wings extending backward along the rim of the pitcher to a distance proportioned to the size of the head. 70

Fifth. The handle of the pitcher, as shown in Figs. 1 and 3, is so formed or decorated as to suggest two parallel cables or ropes knotted together near the top thereof.

What I claim is—

The design for a pitcher or similar article as shown and described.

ALFRED B. EVANS.
